UNITED STATES PATENT OFFICE.

CHRISTEN SMITH, OF SLEMDAL, NEAR CHRISTIANIA, NORWAY.

APPARATUS FOR LOWERING SHIPS' BOATS.

No. 910,594.

Specification of Letters Patent.

Patented Jan. 26, 1909.

Application filed August 14, 1907. Serial No. 388,523.

To all whom it may concern:

Be it known that I, CHRISTEN SMITH, a subject of the King of Norway, residing at Slemdal, near Christiania, Norway, have 5 invented certain new and useful Improvements in Apparatus for Lowering Ships' Boats; and I do hereby declare the following to be a full, clear, and exact description of the invention, such as will enable others 10 skilled in the art to which it appertains to make and use the same, reference being had to the accompanying drawings, and to letters or figures of reference marked thereon, which form a part of this specification.

15 This invention relates to an apparatus for lowering ships'-boats, of the kind wherein the usual "davits" are replaced by suspension posts swinging about horizontal pivots by means of which the boat can be moved 20 far out from the side of the ship before being lowered into the water. Various designs of such apparatus have been tried without, so far as it is known, an arrangement having been provided, that would satisfy the 25 requirements, which professionally should be fulfilled in this kind of appliance.

By the arrangement which forms the subject-matter of this invention stress is laid on giving the apparatus the greatest 30 possible simplicity and such a construction that the manipulations necessary in using the apparatus are of the kind to which a sailor is accustomed in his daily occupation.

The boat rests on chocks which can be 35 quickly removed by means of a system of tackles or similar appliances; the boat then hangs freely in a frame-like contrivance which is capable of turning in a vertical plane on pivots placed considerably lower 40 than the boat and inside its point of suspension. This suspension frame is kept in position by a system of tackles controlled from the boat and these tackles have only to be eased off in order that the boat may be 45 brought away from the side of the vessel ready to be lowered into the water. To the suspension frame are attached bars whose other ends are arranged to be movable in a transverse direction, being at the same time 50 connected with ratchet and pawl arrangements to prevent any inward movement. By this means the rolling of the ship will not cause the suspension frame to turn inwardly while being lowered.

55 One construction of apparatus embodying

this invention is shown in the accompanying drawings.

Figure 1 is a perspective view of the apparatus. Fig. 2 is a cross section of the upper part of a vessel fitted with the improved 60 arrangements of davits, the chocks being removed, with the boat swung outward ready to be lowered. Fig. 2^a is a similar view showing the boat on the chocks. Fig. 3 is a side view of the boat and davit in the 65 latter position. Fig. 4 is a detail longitudinal section of a ratchet mechanism. Fig. 5 is a cross section of the same. Figs. 6, 7 and 8 show on a smaller scale an end 70 view, side view and plan view respectively of a slightly modified construction of the improved arrangements of davits and Fig. 9 is an end view of a third mode of construction.

The boat is suspended in a davit frame *a*, 75 which is preferably made of H-bars and is free to swing, being attached to the deck at *d*, at a point inside that from where the boat is suspended. The two vertical parts of the frame are supported laterally by parallel bars *b* forming a slot between them and which project from the gunwale of the ship back over the deck, so as to form a support for an awning. These guide bars also form a substantially horizontal guide for the 85 inner ends of bars *e* the outer ends of which are fastened to the frame *a*. Each bar *e* is provided at said inner ends with rollers *f* (Figs. 4 and 5) running on flanges formed on the iron bars *b*, and with a pawl *g*, which 90 by means of a counterweight *h* is kept in gear with a ratchet *i* fastened to the under side of a plate *j* which connect the bars *b* in pairs. The object of this arrangement is to prevent the davit frame in a high sea, from 95 going back while the boat is being lowered.

The chocks *k*, on which the boat rests, are kept in a substantially upright position, slanting somewhat outwardly, (see Fig. 3) by two bars *l*, fastened between two lug pieces 100 *m* on the deck by means of a bolt *n* passing through the lugs and through the hole in each bar *l*. A rope *p* connected to each chock passes around pulleys *q* and is connected to the bolt *n* so that when the latter is withdrawn from the holes the pull given to the rope by the withdrawal will cause the chocks 105 to drop.

The davit frame is lowered and raised by means of a rope *r* which passes through blocks 110

$r' r^2$ connected respectively to the frame and ship and the boat is connected with the frame by a tackle s .

The modified constructions shown in Figs. 5 6 and 7 are useful in cases where the feet or pivots of the davit frame are placed at the same level as the chocks. These figures also illustrate an improved arrangement of the boat tackles whereby any movement of the 10 boat in either a transverse or longitudinal direction is prevented. The blocks are divided in such a way that the end of the rope passes through a block t fastened to the davit frame and from there down to the block 15 in the boat. The two parts of the rope u, v will thus make an angle with each other and any swinging of the boat is thereby made impossible.

This construction shown in Fig. 8 illustrates 20 how a single tackle x with two ropes w, w' leading to the davit may be employed instead of two separate tackles for lowering the latter.

In the construction shown in Fig. 9 the 25 stanchion bars b are slanting, their upper ends being attached to a vertical pillar b' while horizontal struts c which form a guide for the bars e are placed lower down.

When the boat is to be lowered into the 30 water the mode of procedure is as follows: The first man arriving should loosen the chocks and turn them down by pulling at

the tackle for the purpose. The boat is now hanging ready for lowering, crew and passengers—all who are going in the boat—take 35 their seats. The men in the bow and stern are ready at the frame tackle. At the word of command the latter are eased off till the frames are in their extreme position. When the proper moment for lowering the boat arrives 40 the one in charge gives the word and the boat tackles are eased off quickly. When the boat is in the water the tackles are cast loose and unhooked and the boat is free.

I claim:—

A boat lowering apparatus, comprising a pivoted davit-frame, angular guides therefor, rigid members having their outer ends connected with the davit-frame, rollers on the inner ends of the rigid members resting on 50 flanges formed on the guides, weighted pawls mounted on said inner ends, racks on the guides adapted to be engaged by said pawls and tackle for operating the frame in combination with suitable chocks situated between the guides adapted to support a boat 55 when the frame is in a raised position.

In testimony that I claim the foregoing as my invention, I have signed my name in presence of two subscribing witnesses.

CHRISTEN SMITH.
